UNITED STATES PATENT OFFICE.

FRED W. KARGE, OF CHICAGO, ILLINOIS.

COMBINATION FIREPLACE AND CONTAINER FOR RADIO RECEIVING SETS.

Application filed April 20, 1925. Serial No. 24,711.

To all whom it may concern:

Be it known that I, FRED W. KARGE, a citizen of the United States, residing in the city of Chicago, county of Cook, and State of Illinois, have invented certain new and useful Improvements in Combination Fireplaces and Containers for Radio Receiving Sets, of which the following is a specification.

- 10 This invention relates to combination fireplace and container for radio receiving sets, and refers more particularly to the utilization of the interior space above the arch of a fireplace in the home, as a container 60
 15 for the accessories of a radio receiving set, including tubes, batteries, sound amplifier, and all wire connections, only permitting the exposure of a panel, dials and rheostat for regulation of the set. 65
 20 In the preferred form of the invention, the walls of the fireplace may be cast in a single piece from any suitable building material, for instance, concrete, and may comprise the exposed front wall and the 70
 25 rearwardly extending side walls integrally bonded thereto. The front wall is recessed adjacent its lower end, say centrally, to provide the usual arch. To simulate the 75
 30 appearance of a fireplace constructed of brick, the arch may be formed with a rearwardly extending portion of a length substantially the length of a standard building brick. The walls themselves however, are materially less than the width of a 80
 35 brick as the integral bonding of the cast form allows a very thin wall to be used 85 without destroying the structural strength thereof. Further, it is desired to reduce the width of the cast form as far as possible, as this is an advantage in handling, 90 and of course, the use of thin walls of required structural strength will permit of light weight construction. 95

The accessories of the radio receiving set 100 are placed in the space between the front wall of the fireplace and the wall of the home, above the arch. The usual front panel and regulating dials are mounted on the exposed face of the front wall of the 105 fireplace above the arch having connection through that wall with the set. A movable door closing the space above the set between the fireplace walls and wall of the house, permits of ready access to the set 110 itself, should it require adjustment or re-

pair. A sound amplifying device or loud speaker communicates with the set and discharges the amplified sound into the space formed by the arch, thus utilizing the natural shape of the arch itself as a medium 60 to further amplify the sound.

When assembled as above described, there are no portions of the radio set visible except the regulating dials and panel board, thus providing a very attractive construction. The fire place is not adapted readily for flame fires of gas, wood, coal and the like, but electrical connections may be made with the base and a flame simulating arrangement placed therein as is usual in 70 numerous types of fireplaces of the present day.

By insulating the radio receiving set, arrangement can be made for the use of flame fires which require a draft. Various other 75 advantages will be brought out in the following description:

In the drawings, Fig. 1 is a front elevational view of the combination fireplace and container for the radio receiving set 80 in actual use in the home.

Figs. 2 and 3 are cross sectional views taken respectively on lines 2-2 and 3-3 of Fig. 1. Fig. 4 is a perspective view of one form of support for the accessories of the radio receiving set. Fig. 5 is a cross sectional view taken on lines 5-5 of Fig. 3. Fig. 6 is a perspective edge view of the fireplace walls illustrating a form of notching for use in joining adjacent bookcases 90 with the fireplace wall.

Referring in detail to the drawings, 1 designates a side wall of a home. First,—describing the method of casting the fireplace as a unitary construction, concrete or other suitable material is placed while wet into a forming mold and allowed to set and dry for the desired length of time. The 95 molded article is then removed and takes the form of a fireplace having a front wall, rearwardly extending side walls and an arch, the entire construction being in a single piece integrally bonded. The surfaces of the walls will be more or less rough, and a surfacing material may be then applied. 100 Any suitable form of surfacing material may be placed thereon, which will present a smooth attractive finish when dry. It is of course understood, that any form of rough finish may be applied, if found desirable. 105

The exposed surfaces of the fireplace have imposed thereon intersecting lines to form any suitable design and which preferably take the form of a brick simulating design.

5 Thus, we have the front wall 2, side walls 3 and 4, arch 5, and a rearwardly extending portion 6 around the arch. This rearwardly extending portion 6 is preferably the length of a standard form of building brick to carry 10 out the illusion of the simulated brick work. The exposed surface of the front wall 2 has the intersecting lines 7 on the surface thereof to simulate standard building bricks.

This unitary construction is adapted to be 15 placed either in homes which are in process of construction, or in homes which have been built for any length of time. It is to be noted that the walls 2, 3 and 4 are very thin compared to the thickness of an ordinary 20 building brick. It is possible, on account of the integral bonding of the material, to secure maximum structural strength with a minimum of thickness, thus materially reducing the weight of a unitary construction 25 of this character.

The construction is adapted to be placed in the home, and may have adjacent thereto the bookcases 8, and provided with the stationary mantel or shelf 9 thereabove.

30 Referring now to some of the novel features of the present invention, the rearwardly extending portion 6 forming the arch, is adapted to contact with the rear vertical wall 10 of the arch, which preferably takes 35 the form shown in Fig. 5, although it is understood that it may be formed in the shape of a crescent or semi-circular, if desirable. The purpose of this particular construction will be hereinafter brought out.

40 The floor of the home is designated at 11, and 12 designates the base of the fireplace.

Above the wall 10 and arch 5 is the horizontal closure element 13 which may be constructed of any suitable material, for instance, wood where a flame fire is not used, or a non-inflammable construction where a flame fire is used. Imbedded in the front wall 2 and above the arch 5 are the brackets 14. These brackets are preferably arranged 45 in spaced pairs having the opposite in-turned lips 15. These lips are adapted to receive and hold in place the L-shaped supporting elements 16, one extension of the L being tapered as shown at 50 17. There are preferably two sets of brackets 14 and L shaped supports 16 as shown clearly in Fig. 2. On the surface of the extension 16 of the support may be transversely mounted a shelf 18.

55 On the shelf 18 is adapted to be placed the base (not shown), on which the accessories of the radio receiving set designated as a whole at 19, are mounted. It is to be understood that these accessories may be mounted 60 within an individual cabinet as shown, or

the use of an individual cabinet may be entirely dispensed with, and the entire construction supported on the base.

The particular construction shown in the drawings, includes a cabinet, and the invention will be explained with the use of this individual cabinet, but it is to be thoroughly understood that this in no way affects the invention. The tubes, batteries and all wire connections are placed within the cabinet 75 19 which has the movable upper door 20. The sound discharged through the wire connecting lines 21 to the unit 22, which discharges the sound into the sound amplifying tubes 23 which preferably take the form of a downwardly tapering megaphone curved in its length so that the sound is gradually amplified during its passage through the device 23, and is discharged from said device into the space formed by the arch. The particular shape of the arch has been carefully worked out in order that the shape may be utilized as a means for further amplifying the sound. This is clearly shown in Fig. 3.

80 A panel board 24 may be counter-sunk into the exposed surface of the front wall 2 of the fireplace directly above the arch. On the panel 24 are the usual regulating dials 25 and rheostat 26 having connections 27 through the front wall with the radio set.

85 It will be readily seen that all of the accessory parts of the receiving set are entirely concealed within the space above the arch of the fireplace including the tubes, all wire connections, sound amplifying device and batteries.

90 Now as a feature of the invention, to readily allow for adjustment or repair of the set, there is provided a movable door 105 28 above the set and closing space between the front wall 2 and rear wall of the house, connected by means of a hinge 29 with the shelf 9.

95 When the unitary fireplace construction 110 is made upon special order for use in homes under construction, the side walls 3 and 4 are provided with the vertical notch 30 to allow for ease in joining and connecting the side walls to bookcases. This is shown 115 in Fig. 6.

120 It is of course, obvious that any form of arch may be provided which is found desirable or suitable, for instance, the arch instead of being round, may be square or rectangular. The wall 10 may take any form which is found desirable in place of the substantially octagonal shape which it now presents.

125 Where it is desired to have a flame fire, it will be readily seen that the accessories to the radio receiving set can be made more compact and moved upward toward the front wall 2 of the fireplace, and an insulated wall placed between these accessories 130

and the walls of the home to provide a draft or stack for the smoke and combustion gases.

It is to be understood of course, that the 5 unitary fireplace construction may be reinforced with any suitable form of expanded metal lath or the like in common use at the time. Further, the arch itself may be reinforced with a curved metal reinforcement, for instance a one inch channel 10 iron.

I have illustrated and described the brackets 14 as being used in pairs. It is to be understood of course, that the 15 particular form of bracket 14 and support 16 may be widely varied without departing from the scope of the present invention. The particular shape or design of this 20 bracket support is not claimed as one of the features of the invention, and any suitable form may be utilized other than that shown.

The front wall 2 of the fireplace may be connected by means of any suitable form 25 of turn buckle tensioning device by anchoring one end of said turn buckle arrangement in the wall of the home, and the opposite end of said turn buckle arrangement in the front wall 2 of the fireplace. Thus, 30 it is possible by adjusting the turn buckle, to vary the tension between the wall of the home and the wall 2 of the fireplace for the purpose of providing a rigid construction.

I claim as my invention:

35 1. A construction of the character described, comprising front and side walls and arch of a fireplace, a supporting structure above the arch for a radio receiving

set and accessories, manually operable regulating means for the set mounted on the 40 exposed surface of a wall of said fireplace having connections through the wall with said accessories, and an amplifying device connected with the set for discharging sound into the space formed by the arch. 45

2. A construction of the character described, comprising front and side walls and arch of a fireplace, a supporting structure above the arch for a radio receiving set and accessories, manually operable regulating 50 means for the set mounted on the exposed surface of a wall of said fireplace having connections through the wall with said accessories, a projecting partition between the crown of the arch and the accessories, 55 and an amplifying device connected with the set for discharging sound into the space formed by the arch.

3. A construction of the character described, comprising front and side walls 60 and arch of a fireplace, a supporting structure above the arch for a radio receiving set and accessories, manually operable regulating means for the set mounted on the exposed surface of a wall of said fireplace 65 having connections through the wall with said accessories, and an amplifying device connected with the set for discharging sound into the space formed by the arch, the accessories and a major portion of the 70 sound amplifying device being concealed from view, and a movable closure member above the accessories support for permitting free and immediate access to said accessories.

FRED W. KARGE.
